DEADEND CONNECTOR WITH ANCHOR MEMBER
John J. Brautigam, Darien, Conn., assignor to Burndy Corporation, a corporation of New York
Filed Sept. 24, 1962, Ser. No. 225,767
3 Claims. (Cl. 174—79)

My invention relates to a deadend connector for physically securing an electrical conductor to an anchorage point.

It is an object of this invention to provide a deadend connector having improved means for securing an anchorage member to the connector body.

A further object is to provide a deadend connector in which the parts thereof may be physically fastened together by crimping and/or mechanical means and which may thereafter be electrically and mechanically connected to a conductor by additional crimping.

A still further object is to provide a deadend connector which includes means for electrically connecting a branch conductor to a dead ended conductor.

Other objects of the invention are to provide a deadend connector that is reliable, which may be readily assembled, and which is inexpensive to manufacture.

I accomplish these and other objects and obtain my new results as will be apparent from the devices described in the following specification, particularly pointed out in the claims, and illustrated in the accompanying drawing in which:

FIGURE 1 is a perspective view of a deadend connector having a looped bail and a connecting tongue, showing the bail fastened to the connector body by crimping;

FIGURE 2 is a perspective view of a deadend connector having a modified bail and showing a body in which the bail has been mechanically fastened thereto;

FIGURE 3 is a partly exploded perspective view of a deadend connector having an eyebolt type of anchorage;

FIGURE 4 is an exploded perspective view of the connector of FIGURE 1 prior to crimping;

FIGURE 5 is a longitudinal sectional view of the deadend connector of FIGURE 2.

FIGURE 6 is a similar view of the deadend connector of FIGURE 3.

Referring to FIGURE 1 of the drawing, reference numeral 10 designates a malleable tubular connector body made of electrically conductive metal. The body may be advantageously formed of a unitary tube, one end of which is flattened and bent to form an integral end wall 24, and a tongue 12 for mounting to an electrically connecting device, not shown. The appearance of a connector body formed in this manner is more clearly illustrated in FIGURES 2 and 5, discussed later in this specification. Apertures 38 may be provided in the tongue to facilitate mounting of a connecting device.

An anchorage member or bail 14 comprising a loop of wire formed into two legs 16 and 18 is inserted through two apertures 20 and 22 in the closed end 24 of the tubular body. In use, one end of a conductor such as a commercial power cable having a fixed mounting at the other end, is secured within the body, and the looped end of the bail is engaged by a hook or the like mounted on a support such as a building or telegraph pole to apply axial tension to the conductor.

As shown in FIGURE 4, a plug 26 having a length less than the internal length of the connector body is employed to retain the bail to the connector body. The plug end is preferably formed to mate with the inner surface of end wall 24, and may be grooved, as at 28

2

and 30, to permit the legs 16 and 18 to be received therein. The ends 32 and 34 of the legs are inwardly bent to engage the forward surface 27 of the plug to prevent separation by pulling, although the ends may be formed in other obvious shapes serving to resist separation. Forces applied to the bail and body in use are thus transmitted between the two by compressing the plug against body end wall 24. Bail retention forces are thus derived from engagement of the bail and plug 26, and the bail material is chosen so that the force required to straighten or separate the ends is greater than the forces ordinarily encountered in use.

In assembling the connector, the two legs of the bail are first inserted through the apertures 20 and 22. The plug is positioned between the two legs 16 and 18 and the leg ends inwardly bent as shown. The ends may however be formed prior to inserting the bail into apertures 20 and 22 if the apertures are suitably enlarged. The bail is then pulled tight until the ends 32 and 34 are seated against surface 27 and the plug is seated within the tubular sleeve against the inside surface of end wall 24.

In the crimped form, the connector wall is then crimped, as at 36, locking the plug in position. The crimps may preferably be positioned to include the legs 16 and 18 to provide retaining force in the form of a snub connection.

The remainder of the tubular sleeve in front of the plug is used for inserting a conductor 50 (see FIGURES 2 and 5) therein and crimping to establish the electrical connection. As an example, in a tubular connector having a length of 3.25 inches, the plug length need only be 0.50 inch, allowing 2.75 inches for crimping the conductor therein.

35 In the deadend connector shown in FIGURES 2 and 5, employing mechanical bail fastening means, parts identical to corresponding parts of FIGURES 1 and 4 have been identically numbered and include an identifying "a" suffix. A threaded cap 42 is positioned in front of the plug 26a within the connector body 10a. The inner surface of the connector 10a is similarly threaded at this point as at 47 to engage the cap and to permit it to be tightened against the plug. Slot 44 may be provided in the cap for inserting a rotating tool 40 therein. The front surface 27a of the plug is grooved as at 45 to provide seats for the bent over ends of legs 16a and 18a which may be identical to the ends 32 and 34 of FIGURE 4, and to permit the cap to engage the surface upon tightening. This locks the inwardly bent ends against forward movement to prevent inadvertent disassembly of the plug, bail and body.

Other suitable types of mechanical securing means for engaging a cap 42 to connector body 10a may be used in place of the threading shown.

55 In the design shown in FIGURE 3 and FIGURE 6, the anchorage member comprises an eyebolt 14b having a stem portion 53 which terminates in a flat plate or "mushroom" head portion 52. The head may be integral with the stem or secured thereto by any suitable means. 60 The plug 26b in this version may be divided into two mating sections 26c and 26d, each having a groove 28 to receive the eyebolt and form a bearing collar engaging the stem side of head 52. The end wall 24b of connector body 10b is apertured as at 20b to allow the 65 eyebolt to extend therethrough.

When crimped as at 36b, after the plug sections have been assembled and the eyebolt tightly drawn to position 14bb, the plug and eyebolt are secured to the connector. Knurling of the stem 53 proximate the head 52, as at 54 may be provided to insure increased retention when the plug sections are forced together about the bolt by

crimping or by the camming action of the rounded inner surfaces of end wall 24b.

In the foregoing, there has been provided an inexpensive type of deadend which is reliable in operation and is quickly and easily installed. The retention and force transmitting plug may be either crimped or mechanically secured in position, allowing the rest of the tubular body to be utilized for crimping the inserted conductor. Retaining forces applied to the anchorage member are distributed through the retention plug over substantially the entire inner surface of the body end wall thus reducing unit pressures on the body.

I have thus described my invention, but I desire it understood that it is not confined to the particular forms shown and described, the same being merely illustrative, and that the invention may be carried out in other ways without departing from the spirit of my invention, and therefore I claim broadly the right to employ all equivalent instrumentalities coming within the scope of the appended claims, and by means of which objects of my invention are obtained and new results accomplished since the particular embodiments herein shown and described are only some of the many that can be employed to obtain these objects and accomplish these results.

I claim:

1. An anchoring connector for a conductor, comprising: a longitudinally extending tubular body member formed of malleable metal and including an open forward end for receiving a conductor and a closed rearward end wall having an opening therethrough; a substantially cylindrical plug member telescopically disposed within said body member and having a longitudinal opening therein; said plug member further including a substantially transverse forward surface portion and a rearward end portion adapted to abut the inner surface of said body member end wall; an anchor member longitudinally extending through said body member end wall opening and said plug member opening, and having means external to said body member for mounting to a support; said anchor member being provided with a transversely bent portion within said body member for

engaging said plug member forward surface to prevent rearward movement of said anchor relative to said plug; said body member being crimped in a plane intersecting said plug member and said anchor member to secure said members to said body member.

2. The anchoring connector of claim 1 wherein said body member end wall includes a second opening therethrough; said plug member includes a second longitudinal opening; said anchor member is of generally U-shape having a base and two longitudinally extending legs, said base being disposed externally of said body member with said legs extending through said end wall openings and said plug member openings into said body member; and said transversely bent portion is formed at the end of one of said legs and a second transversely bent portion is formed at the end of the other of said legs.

3. The anchoring connector of claim 1 wherein said tubular body member includes an integral tongue portion, for making electrical connections thereto, formed by flattening a length of the tubular body.
